J. BLACKBURN

EARTH ANCHOR

Filed June 23, 1924

INVENTOR:
JASPER BLACKBURN.
BY Edwvng E. Long
ATTORNEY.

UNITED STATES PATENT OFFICE.

JASPER BLACKBURN, OF WEBSTER GROVES, MISSOURI.

EARTH ANCHOR.

Application filed June 23, 1924. Serial No. 721,929.

To all whom it may concern:

Be it known that I, JASPER BLACKBURN, a citizen of the United States, and resident of the city of Webster Groves, county of St. Louis, and State of Missouri, have invented certain new and useful Improvements in Earth Anchors, of which the following is a specification, containing a full, clear, and exact description, reference being had to the accompanying drawings, forming a part thereof.

My invention relates to improvements in earth anchors and has for its primary object a construction of anchor which may be anchored into the earth at spaced apart positions and the upper portion of the anchor compressing the earth on the remaining or lower portion of the anchor.

In the drawings:

Fig. 1 is a side elevation of my improved anchor contracted and in a position to be set into the anchor hole formed in the earth;

Fig. 2 is a top plan view with the anchor rod in section;

Fig. 3 is a side elevation of the anchor set in the hole and anchored therein when in use;

Fig. 4 is a top plan view of the lower portion or expandable part of the anchor, the upper portion being removed, and the rods which expand the anchor blades, and the anchor rod being in section;

Fig. 5 is a section taken on the line 5—5 of Fig. 4 and looking in the direction of the arrow illustrating the means by which the anchor blade expanding rods are secured to the blades; and

Fig. 6 is a sectional elevation taken on the line 6—6 of Fig. 1 looking in the direction of the arrows.

Referring to the drawings—7 indicates the bottom or crown plate and is provided at diametrically opposite portions with guide flanges 8 and 9. The purpose of these is to guide and hold in position the anchor blades 10 and 11, which are adapted to slide in their in and out movements between these guide flanges. Formed integral with the bottom or crown plate 7 and projecting from the upper surface thereof is an angular stud 12, this angular stud 12 is provided near its base and on opposite sides thereof with slots 13, and on its upper end with a flange 14 on opposite sides thereof.

Formed through the bottom or crown plate and the angular stud 12 is an opening

15 in which the anchor rod 16 is located, and located on the lower end of the anchor rod 16 is a nut 17 for securing the anchor rod 16 to the anchor. The anchor blades 10 and 11 are provided with slots 18 in which the angular stud 12 is mounted and these blades 10 and 11 slide in the slots 13 formed in the angular stud 12. It will be noted in this connection that the angular stud 12 also answers as a guide for the movements of the anchor blades 10 and 11.

19 and 20 form another pair of anchor blades which are mounted or superimposed on the first mentioned blades 10 and 11, but 70 are arranged to expand together and be collapsed or drawn in a direction at right angles to the movement of the blades 10 and 11. The blades 19 and 20 are likewise provided with slots 21 and 22 in which the 75 angular stud 12 is located. These blades 19 and 20 are located beneath the flanges 14 and move in and out over said stud. It will also be noted that these blades 19 and 20 are positioned so as to move over the 80 flanges 8 and 9 (see Fig. 1).

The crown or base plate 7 is substantially circular and all the anchor blades have rounded outer edges slightly sharpened and when contracted practically coincide with the periphery of the crown or base plate 7. The outer edge or terminal portion of each anchor blade is provided on its upper surface with an integral pocket 23. This pocket is open at its top and inner end, or 85 in reality is merely composed of two side walls and an end wall uniting the same. The inner surfaces of the side walls of each pocket are provided with grooves 24, and connecting the grooves is a slight flange 25, and a shoulder 26 arranged in front of the 90 grooves. The pockets in each plate are formed precisely alike and as previously described. These pockets are arranged to receive rods or links 27 for expanding the anchor blades. It will be observed from Figs. 5 and 6 that each end of these rods is provided with opposite ribs or shoulders 28 and on the inside of the shoulders with recesses 29. In order to connect the ends of 100 the rods in the pockets 23 the shoulders 28 formed on the rods are inserted in the recesses or grooves 24. It will be understood to permit this insertion the rods must be held almost horizontally. After this is 105 done, if desired, the corners 30 may be bent 110 in the recesses 29 formed in the rods adja-

cent the shoulders. By the previous construction it will be noted that the lower ends of the rods 27 are pivotally united to the outer ends of the anchor blades 10, 11, 19 and 20. The upper end of the rods 27 are formed similar to the lower ends and are connected to a frusto conical member 31, this member is of skeleton formation, and is provided with cut away portions 32 so that when this member is collapsed the rods 27 may pass therein (see Figs. 1, 2 and 3). These cut away portions also permit the upper ends of the rods to be connected in the pockets formed in the conical member, as illustrated in Fig. 6. It may be noted in this connection that the upper ends are first connected in the sockets in the conical member and then the lower ends are connected in the sockets in the anchor blades.

20 The frusto conical member 31 is formed on its underneath surface with a series of sockets 33 which are constructed like the sockets formed in the ends of the anchor plates and in which the upper ends of the rods 27 are located. It will be noted in this connection that the sockets in the anchor plates and the sockets in the conical member 31 are formed the same, likewise both ends of the rods 27 are constructed alike, and the upper ends of the rods 27 are seated in the sockets formed in the member 31 in the manner described with relation to connecting the lower ends of the rods 27 in the sockets 23 formed on the anchor plates.

30 The conical member 31 has an opening 34 through which the anchor rod 16 passes, the member 31 is adapted to be moved downwardly on this anchor rod in the expansion of the blades 10, 11, 19 and 20. In other words by forcing this conical member 31 downwardly the blades are expanded, as illustrated in Figs. 3 and 4, and when it is moved up, as in Fig. 1, the blades are contracted.

40 When the anchor has been made as previously described, it is adjusted in the form shown in Figs. 1 and 2 and then set in the hole 35 (Fig. 3). After it has been seated in the hole, the anchor blades 10, 11, 19 and 20 are expanded by hammering on the conical member 31 and these blades are forced out into the earth, and when the blades have been expanded, it will be noted from Fig. 3 that the conical member will be seated on the uppermost anchor blades. When it has been expanded in this form, a body of rock 36 is thrown into the hole on top of the conical member 31 and tamped, this tamping will wedge the conical member in the hole. It will also pack the earth above the anchor blades. It will be noted in this connection that my anchor is anchored in the earth by means of the blades and by means of

the conical member 31 and body of rock. It will further be noted that the upper surface of the member 31 is honey-combed or roughened, so as to catch the rock and not let it pass through or slip off of the surface.

It will be observed that the conical member 31 performs two functions, by driving down on it, it expands the blades, and when seated and crushed rocks tamped thereon on top of it, it answers as an auxiliary anchoring means.

Having fully described my invention, what I claim is:—

1. An anchor comprising a base plate, an anchor rod secured thereto, a pair of expanding blades mounted on said base plate, a conical member adapted to slide over the anchor rod, a pivotal connection between the expanding blades and cone whereby when the cone is pressed down, the blades are expanded, said cone adapted to be wedged into a hole in a position above the expanding plates.

2. An anchor comprising a base, a plurality of expanding blades mounted on the base, an anchor rod secured to the base, a conical member slidably mounted on the anchor rod and pivotally connected to the expanding blades for expanding the same, when said cone is moved downward.

3. An anchor comprising a base, expanding blades slidably mounted on the base, an anchor rod secured to the base, a conical member provided with an open-work top surface mounted on the anchor rod and links pivotally connected to said cone and expanding blades for expanding the same, when said cone is moved toward the base, said cone adapted to be wedged into a hole by means of a body of crushed rock or like material, and the earth above the expanding blades be simultaneously packed thereby.

4. An anchor comprising a base, a plurality of expanding blades mounted on the base, an anchor rod secured to the base, a conical member provided with a roughened upper surface and cut away portions slidably mounted on the anchor rod and pivotally connected to the expanding blades for expanding the same, when said cone is forced toward said base.

5. An anchor comprising a base, expanding blades mounted on the base, an anchor rod secured to the base, a conical member mounted on the anchor rod, and connections between the conical member and the expanding blades whereby said blades are expanded when the conical member is moved toward the base.

In testimony whereof, I have signed my name to this specification.

JASPER BLACKBURN.
